UNITED STATES PATENT OFFICE.

GEORGE R. JOUGHINS, OF MONCTON, NEW BRUNSWICK, CANADA.

CAR-ROOF.

1,136,962.

Specification of Letters Patent.

Patented Apr. 27, 1915.

Application filed September 13, 1913. Serial No. 789,720.

To all whom it may concern:

Be it known that I, GEORGE R. JOUGHINS, a citizen of the British Empire, residing in Moncton, in the Province of New Brunswick, Dominion of Canada, have invented a new and useful Improvement in Car-Roofs, of which the following is a specification.

The invention relates to metal car roofs, and more particularly to the shape of the metal roof sheet whereby it is provided with water-deflecting and conducting parts and gutterways, which also greatly stiffen the sheet; and the invention further relates to combinations of such sheets with the roof sheet supporting elements of the car roof frame; and the invention consists in the parts and combinations thereof hereinafter set forth and claimed.

In order to make the invention more clearly understood there are shown in the accompanying drawings means for carrying the same into practical effect, without limiting the improvements, in their useful applications, to the particular constructions which, for the purpose of example, have been delineated.

In the said drawings:—Figure 1 is a transverse vertical section of a portion of a freight car roof embodying the invention, as applied in an inside metal car roof. Fig. 2 is a side view of the same partly broken away and partly in section. Fig. 3 is a plan view of one of the sheets formed with water-deflecting projections or embossments of oblong form. Fig. 4 is a perspective view of a portion of the roof sheet shown in Fig. 3, on a larger scale, and showing also parts of the roof frame elements. Fig. 5 is a plan view, the sheet being formed with round embossments, and with a single gutter. Fig. 6 is a perspective view showing the sheet without embossments and formed with another form of single gutter.

Referring to the drawings, 1 indicates the ridge pole of a freight car roof; 2 the side plates; 3, 4 the carlines; 5 the purlins; 6 the sub-purlins; 7 the top sheathing; 8 the inner fascia; 9 the spacing blocks; 10 the outer fascia and 11 the metal roof sheets. The side sheathing is shown at 19. The ridge pole is formed with lateral grooves 12 into which the inner ends of the carlines enter, which grooves are made of sufficient height to receive also the ridge ends of the roof sheets 11. The roof sheets extend over and rest at their middle portions on the alternate

carlines 4, and at their side edges enter grooves 13 formed in the other alternate carlines 3. The said edges of the sheets are formed with upwardly inclined flanges 14 which enter the said grooves 13, and the grooves have or may have the same inclination. The sheet is bent a little downward, from its middle toward its sides, so that its two sides or halves decline from the top of the carline 4 toward the lower part of the carlines 3.

At or near the flange 14 and between the same and the conterminous half of the sheet there is formed a gutter 15 running from the ridge to the eaves of the car. Such gutter may be bounded at its other side by a wall 16 which extends up to about the level of the main part of the sheet (Fig. 5); but in Fig. 6 is shown a form of sheet in which the gutter is produced at the angle between the flange 14 and the main part of the sheet. The gutter may be double, as shown in Figs. 2, 3 and 4, thus insuring against any water reaching the joints at 13, 14; and also greatly stiffening the side borders of the sheets.

The main portions of the sheets may be plane, as shown in Figs. 2 and 6. Preferably, however, they are formed with embossments to stiffen them and aid in deflecting water more directly to the gutters. In Figs. 3 and 4 such embossments are shown at 17, of oblong form, those at the middle of the sheet extending across the carline 4 and the others being inclined at an angle downward toward the gutters and toward the eaves of the car. The embossments 17 are also arranged to lap a little past one another, so that water escaping from the lower end of one embossment will be caught on the upper end of the next and thereby deflected toward the gutter rather than toward the eaves of the car. The embossments give great stiffness to the sheet, and the extending or lapping of the embossments past one another very much increases this stiffening effect. This arrangement of the embossments may be such (Fig. 3) that a continuous straight line cannot be drawn across the sheet in any direction without crossing one or more of these stiffening projections. The embossments are or may be drawn out from the body of the sheet by a pressing operation, so as not to materially reduce its horizontal area but so as to considerably increase its depth and stiffness; and the said lapping arrangement enables

the embossments to conduct water in a definite desired direction.

It results from the described arrangement of embossments that there are formed 5 runways for water, such runways being arranged diagonally across or partly across each plate. The said runways may be continuous or may not be continuous, depending upon the form or shape of the embossments, 10 which may be of various forms. A circular or hemispherical form of embossment is shown at 18 in Fig. 5. The said deflection of the water is aided by the fact that one half of each roof sheet pitches two ways, 15 toward the gutter (longitudinally of the car) as well as from the ridge to the eaves of the roof.

The water is delivered by the gutters at 20 the eaves of the car, over the inner fascia and through the space between the two fascias, the said space being maintained by the blocks 9.

The described roof sheet may be used either for an inside or an outside metal car roof. In the former case it conducts away 25 as described, any leakage through the top sheathing. The sheet is so combined with the ridge pole, carlines and side plates that it may be slid endwise outward and removed, so that repairs and the replacement 30 of any damaged sheet are facilitated.

The directions in which water is conducted by the embossments are shown at 20 in Figs. 3 and 5 by a dotted line.

35 It will be understood that various forms of embossments which will carry the described invention into effect may be used, in place of the particular forms illustrated.

What is claimed is:—

40 1. In a car roof, in combination: carlines formed with grooves in their sides; and metal roof sheets hipped at their middle portions, formed with gutters along their sides to which gutters the two halves of 45 the sheets pitch from the hip, and having side flanges fitted in the said grooves; substantially as specified.

2. In a car roof, in combination: carlines formed with grooves in their sides; metal 50 roof sheets formed with gutters along their sides and having side flanges fitted in the said grooves; and intermediate carlines under the roof sheets from which the sheets pitch toward the said gutters, the two sets 55 of said carlines alternating with each other; substantially as specified.

3. In a car roof, in combination: a roof 60 frame; and roof sheets supported thereby and formed with gutters along their edges leading toward the eaves, and pitched toward the eaves and also longitudinally of the car from their middles to the edge gutters; substantially as specified.

4. In a car roof, in combination: a roof 65 frame; and roof sheets supported thereby

and formed with marginal gutters and pitched toward the eaves, and also pitched longitudinally of the car, the said roof sheets being hipped at their middles and pitching from the hip to the said gutters; 70 substantially as specified.

5. In a car roof, in combination: a roof frame; and roof sheets supported thereby and formed with embossments arranged out of line with each other and lapping so as 75 to direct water longitudinally of the car and toward the eaves; substantially as specified.

6. In a car roof, in combination: a roof frame and roof sheets supported thereby 80 and formed with gutters, and with embossments arranged out of line with each other and lapping, so as to direct water toward the gutters and toward the eaves, substantially as specified. 85

7. In a car roof, in combination: a roof frame; and roof sheets supported thereby and formed with oblong embossments arranged out of line with each other and lapping so that the water is directed by successive embossments toward the transverse edges of the sheets; substantially as specified. 90

8. In a car roof, in combination: a roof frame; and roof sheets supported thereby 95 and formed with oblong embossments arranged out of line and lapping to direct water longitudinally and laterally of the car by its flowing along successive embossments; substantially as specified. 100

9. In a car roof, in combination: a roof frame comprising a ridge pole, and carlines having grooves at their sides, and roof sheets hipped at the middle, formed with marginal gutters leading toward the eaves, 105 and with embossments on the longitudinally inclined surfaces of the sheets, and having side flanges in the grooves of the carlines; substantially as specified.

10. In a car roof, in combination: a roof 110 frame comprising a ridge pole formed with grooves at its sides, and carlines having their ends in the grooves of the ridge pole, the alternate carlines being formed with grooves at their sides; and roof sheets 115 formed with marginal gutters running toward the eaves, and having side flanges fitted in the said grooves of the carlines, the sheets being hipped at the middle and passing over the intermediate carlines; substantially as specified. 120

11. In a car roof, in combination: a roof frame comprising a ridge pole formed with grooves at its sides, and carlines having their inner ends in the grooves of the ridge 125 pole, the alternate carlines being formed with grooves at their sides; and roof sheets hipped at the middle, formed with marginal gutters and with oblong embossments on the longitudinal inclines of the sheets, hav- 130

ing side flanges in the said grooves of the carlines, and passing at the hips over the intermediate carlines, and having their inner ends in the grooves of the ridge pole; substantially as specified.

12. A metal sheet for car roofs, hipped at the middle and formed with side flanges and gutters to which the sheets pitch from the hip, and with embossments on the inter-

mediate longitudinally inclined parts of the 10 sheet; substantially as specified.

Signed by me on the 8th day of August, 1913, in the presence of two subscribing witnesses.

GEORGE R. JOUGHINS.
